BRACKET FOR ATTACHING LEGS TO STACKING TABLES

Howard Barry, 335 Parkville Ave.,
Brooklyn, N.Y. 11230

Filed Oct. 9, 1967, Ser. No. 8,933

Term of patent 14 years

(Cl. D54—1)

FIG.1

FIG.2

FIG.3

FIG.4

FIG.6

FIG.5

FIG. 1 is a perspective view of my bracket for attaching legs to stacking tables;

FIG. 2 is a side view thereof;

FIG. 3 is a top view thereof;

FIG. 4 is a bottom view thereof; and

FIGS. 5 and 6 are end views thereof.

I claim:

The ornamental design for a bracket for attaching legs to stacking tables, as shown.
